UNITED STATES PATENT OFFICE.

ABRAHAM ABELSON, OF NEW YORK, N. Y.

SANITARY VESSEL.

1,095,538.

Specification of Letters Patent.

Patented May 5, 1914.

Application filed May 17, 1912. Serial No. 697,913.

To all whom it may concern:

Be it known that I, ABRAHAM ABELSON, a citizen of the United States, residing at the borough of Manhattan, city of New York, county of New York, and State of New York, have invented certain new and useful Improvements in Sanitary Vessels, of which the following is a specification.

My invention relates to improvements in sanitary vessels, and the object of my invention is to provide a cup or receptacle which may be easily cleaned and kept in a sanitary condition.

Figure 1 is a vertical section of the device. Fig. 2 is section of the device as the line 2—2 in Fig. 1. Fig. 3 is a vertical section of an optional form of the inner cup member or skin.

Similar characters refer to similar parts throughout the several views.

My device is peculiarly adapted to use in shaving cups, and comprises a two part case or member, consisting of a base 1 having an annular seat arranged interiorly and formed by an inwardly projecting annular flange 2, and a cup member 3 seated in the upper edge section 4 of the base 1 and secured thereon by a hinge 5. I also provide, opposite the hinge, a catch, comprising a flat spring 6 secured to the base by means of rivets 7 and bearing a latch member 8 adapted to engage a projection 9 on the base of the cup member 3. An inner skin or cup 10 is adapted to be placed within the cup member 3 and to fit therein. This skin 10 is preferably formed of water-proof paper, or other inexpensive and nonimpregnable material. Disks 11 are provided to fit in the upper section 4 of the base member 1 and to rest upon the flange 2 and are preferably formed of cardboard or other compressible material, and of such thickness that when the cup member 3 is closed down upon the disk and engaged by the latch 8 the disk 11 will be so compressed as to form a substantially water-tight joint. The disk 11 is preferably pressed out to form a seat 12 surrounded by an annular marginal section.

My device is peculiarly adapted for use as a sanitary shaving cup, and for this purpose I provide interchangeable counterpart disks 11 provided with saponaceous material 11'. These disks 11 are interchangeably seated in the upper section of the base member 1, and the cup member 3 is latched down upon the disk 11 and the skin 10 is placed

within the cup member 3. A sufficient quantity of soap or like material 11' is provided in the seat 12 of the disk 11 to provide the necessary lather for an individual shave, and the lather is intended to be worked up in the cup in the usual and well known manner. After each use the cup is opened and the disk 11 and the skin 10 are removed and destroyed, and this operation is repeated each time the device is used, the disk 11 and skin 10 being renewed for the purpose, and it is therefore unnecessary to wash the cup, and for each use a new and sanitary surface and soap are provided.

When desired, an interior skin may be provided as shown in Fig. 3 which comprises a cup-like member in which the sides 13 and base 14 are united, and the soap in the base may be covered for purpose of transportation and sale, by a light sheet 15 which protects the soap from dust and foreign substances, and is easily removed. I prefer to use for this purpose a light sheet of tissue paper which is held in place by adhering to the soap but which will be caused to roll up and uncover the soap by the action of the moist shaving brush applied thereto, or if desired, this sheet 15 may be held in position by any adhesive substance or paste and is broken or rolled off by the application of the wet shaving brush applied in the usual manner to work up a lather. When this form of cup lining is used, it is unnecessary to open the cup member 3 but the lining may be placed within the holder or cup 3 and used and removed as above described.

While this device is particularly adapted to shaving cups, it is obvious that it is equally useful in other fields in which it is desired to have a receptacle which is watertight and at the same time capable of being easily cleaned, as the removable bottom renders it very easy to clean the lower part of the cup, and there are no crevices such as frequently occur in receptacles having a bottom and sides formed of separate pieces.

Having thus described my invention, what I claim is:

1. In a device of the character described the combination of a base member and a cup member, means for holding the base member and cup member in engagement, a removable disk in the base member adapted to form a bottom for the cup member and an interiorly arranged and removable skin

within the cup member substantially as shown and described.

2. In a device of the character described, a cup member, a removable skin therein, a bottom disk provided with a seat and a saponaceous material therein, substantially as shown and described.

In testimony whereof, I have signed my

name to this specification in the presence of two subscribing witnesses, this 15th day of 10 May 1912.

ABRAHAM ABELSON.
